UNITED STATES PATENT OFFICE.

ERNEST GILMORE GARDNER, OF BROOKLYN, NEW YORK.

MEANS FOR SINKING CONCRETE PILES.

Application filed December 5, 1919. Serial No. 342,636.

To all whom it may concern:

Be it known that I, ERNEST GILMORE GARDNER, residing at Brooklyn, in the county of Kings and State of New York, have invented certain new and useful Improvements in Means for Sinking Concrete Piles, of which the following is a specification.

In the sinking or driving of concrete piles it is the common practice to form the pile by driving a tubular metal shell having its lower end covered with a cap or closure into the earth and to either fill the shell with concrete in a plastic condition before it has been driven into the ground or after it has been driven. The shell is then withdrawn leaving the concrete within the hole formed, either immediately after the driving operation is completed or is allowed to remain for a sufficient time for the concrete to partially set, depending upon the nature of the soil.

As the pile shells have heretofore been constructed, many difficulties have been encountered in the withdrawal of the shell, for due to the adhesion between the concrete and the interior of the shell, the power required for withdrawing the shell is very great, and it is frequently necessary to deliver a number of downward blows upon the concrete as the power is exerted upon the shell, to loosen the shell from the concrete, again as the shell is being withdrawn, it frequently happens that the upper portions of the concrete are carried upwardly away from the lower portions thereby resulting in the formation of voids.

The principal object of this invention therefore, is to provide a new and improved construction of a pile shell which will obviate the difficulties hereinbefore enumerated.

A further object is to provide means whereby air may be supplied to the earth cavity for preventing the formation of a vacuum beneath the withdrawing shell.

A further object is to provide a pile shell made of detachably connected sections in order that the length of the pile may be made in accordance with requirements.

For the accomplishment of these and such further objects as will hereinafter be apparent to those skilled in the art to which this appertains, the invention consists in the construction, combination and arrange-

ment of parts herein specifically described and illustrated in the accompanying drawings, wherein is shown a preferred embodiment of the invention, but it is to be understood that changes, variations and modifications may be resorted to which fall within the scope of the claims hereunto appended.

Figure 1 is a longitudinal sectional view thru a pile shell constructed in accordance with this invention.

Figure 2 is a similar view illustrating the effect of withdrawing the shell after the concrete material has been placed therein.

Figure 3 is a longitudinal sectional view thru a pile of this invention formed of a plurality of superposed sections.

Figure 4 is an enlarged fragmentary detail view illustrating the manner of connecting together the sections of the shell shown in Fig. 3.

Figure 5 is a longitudinal sectional view of a pile shell illustrating a modified construction.

Figure 6 is a transverse sectional view taken upon the plane of line VI of Fig. 5.

Figure 7 is a transverse sectional view illustrating a further modification.

Figure 8 is a similar transverse sectional view illustrating a still further modification.

Figure 9 is a longitudinal sectional view of a pile shell embodying a further modification.

Figure 10 is a plan view of the blank from which to form the inner cylinder shown in Fig. 9.

Figure 11 is a transverse sectional view taken upon the plane of line XI of Fig. 9.

Figure 12 is a transverse sectional view thru a pile shell constructed in accordance with this invention, and being of a different cross sectional contour from the cross sections illustrated in the other Figs., and

Figs. 13 to 19 illustrate the manner of employing this invention in connection with the use of pre-cast piles.

Referring to the drawings, the reference character L indicates a pile shell which may be of any appropriate cross section but usually is circular as seen in Figs. 6, 7 and 8. The lower end of the shell L is provided with a driving point G arranged to close its lower end and to serve as means to facilitate entrance of the shell into the earth during the driving operation.

One of the essential characteristics of the

shell of this invention consists in making the same tapered interiorly so that its inner diameter at the lower end, as at 1, is greater than the inner diameter at the upper 5 end, as at 2. The interior surface of the shell is preferably smooth and the taper is gradual and uniform from end to end. The exterior diameter of the shell may also be tapered, if desired, so that the exterior diameter at the top is greater than the exterior 10 diameter at the bottom, but this is ordinarily not necessary.

In using this shell the concrete material, as H, is placed therein, either before or after 15 the shell is driven into the earth, and is preferably allowed to remain undisturbed for a sufficient period to allow the concrete material to set sufficiently to enable it to maintain its own pile formation. The shell is 20 then withdrawn, as suggested by Fig. 2. In withdrawing the shell the natural result of the interiorly tapering shaped shell is that all portions of the interior surface of the shell will move in a direction away from the 25 surface of the concrete material with the initial upward movement of the shell, and as the upward movement of the shell progresses the space between the concrete material and the shell will gradually increase.

30 After the shell has been withdrawn the surrounding earth naturally falls in against the column of concrete and fills the space left by the withdrawal of the shell.

It should be noted here that this invention 35 is not to be understood as limited in any way to the idea of allowing the concrete material to set before withdrawing the shell for it is obvious that the shell might be withdrawn immediately after the concrete material is 40 poured thereinto. In fact this procedure has a certain advantage which is important; namely, of allowing the concrete material itself to spread into the space left by the removal of the shell. A better bond is thus 45 afforded between the column and the surrounding earth. In this instance detachment of the shell from the sides of the column of concrete material is, of course, exactly the same as before altho the concrete 50 material, being soft, will follow to a certain extent and maintain contact with the shell but the pressure of the concrete material against the surface of the shell, however, will naturally be greatly relieved and there 55 will be little or no effective tendency for the shell to lift away upper portions of the concrete material.

Suitable means such as the opening 3, may 60 be provided to facilitate the lifting out of the shell.

As illustrated in Fig. 3 the shell may be 65 made up of a plurality of super-posed sections, as 4, 5 and 6, said sections being connected together preferably by having threaded engagement with each other as seen at 15

in Fig. 4. In using the plurality of sections the section 4 is driven into the earth and filled with concrete material before the next section 5 is connected, section 5 is then connected and the connected sections are 70 then driven until the shell is sunk to the desired depth, after which section 5 is filled with concrete. The section 6 is now connected and likewise driven and filled. Any appropriate number of sections may in this 75 way be connected according to the depth to which the bottom of the pile should be extended. All of the sections thus connected are tapered interiorly so that the taper extends continuously from the upper to the 80 lower end of the pile, and the interior diameters at the lower end of each section corresponds with the interior diameter of the upper end of the adjacent section.

In Figs. 5 and 6 is illustrated a simple 85 method of producing the interiorly tapered shells. This consists of providing an outer cylinder 7, which may be a length of ordinary pipe or tubing is of substantially uniform diameter and thickness thruout and 90 then providing an inner cylinder 8 which is tapered and fitted into the cylinder 7. Rivets or other appropriate means, as 9, may be provided for connecting the two cylinders together.

The cylinder 8 may conveniently be provided from a piece of sheet metal which has been rolled to a tapered thickness, the sheet being bent around so as to fit into the cylinder 7, the cylinder 7 serving to hold the cylinder 8 in its correct condition at all times. 100

In fitting the cylinder 8 into the cylinder 7 it is desirable to provide a small space, as indicated at 10, between the longitudinal edges of the sheet from which the cylinder 8 105 is formed so that when the cylinder 8 is in position within the cylinder 7 said space will constitute a groove extending the full length of the shell. The provision of this groove permits admission of air downwardly to 110 avoid the formation of a vacuum beneath the lower end of the shell while the shell is being lifted out, thus enabling the shell to be much more easily removed.

In Fig. 7 is illustrated a cross section 115 which corresponds to Fig. 6 but being taken thru a shell which is made of a single thickness of material, in which one or more grooves, 11, may be provided longitudinally thereof to serve the same purpose as the 120 groove 10.

In the modification shown in Fig. 8 the shell may be made of inner and outer cylinders, as 13 and 14, similar to those shown in respect to Figs. 5 and 6, and one of said cylinders, for instance the inner cylinder 13, 125 may have the grooves 12 cut therein in its surface which lies against the surface of the other cylinder. In this way the concrete material within the shell is kept away from 130

the passages so that a better circulation of air downwardly to the bottom of the shell is assured.

Where the shell is made of two cylinders, as 7 and 8, connected together, and the abutting surfaces are not finished to an accurate fit, the unevenness of said surfaces will obviously provide a certain amount of air space between said two surfaces thru which air may flow to the bottom of the cylinder whether the above mentioned grooves between said surfaces are provided or not.

In the modification shown in Figs. 9 to 11 outer cylinder 7 may be similar to the outer cylinder in Fig. 5 while the inner cylinder, as 13, is made up from a piece, as 16, of ordinary sheet metal or other suitable material of uniform thickness cut to appropriate shape, as shown in Fig. 10, and then rolled into cylindrical form with its inclined edges 17 abutting together so that the tapered cylinder 13 is produced. The mating edges of this cylinder may be connected in any appropriate manner, if desired, and the lower end is of an external diameter to fit neatly within the lower end of the cylinder 7.

Any suitable means may be employed for holding the cylinder 13 in appropriate concentric position within the cylinder 7 and for this purpose a plurality of rings 18 arranged between the two cylinders at spaced intervals along the length thereof.

It should be here mentioned that a certain advantage might be attained by connecting the rings to the cylinder 13; namely, that after a shell and its contents of concrete material are in position within the earth the shell 13, carrying said rings, may be first lifted away, leaving the cylinder 7 undisturbed. Thereafter the cylinder 7 may be removed. This method of procedure may be a desirable one in dealing with certain classes of earth, for instance, where it is desired to hold back the earth until the concrete has become fully set after the removal of the cylinder 13, or where for any other reason it is desirable to withdraw the inner cylinder alone.

The cylinders 7 and 8 in Fig. 5 may be disconnectible from each other to the same purpose if desired.

Suitable openings, 19, may be provided thru the rings 18 for the free circulation of air. These openings may be directly thru the material of the rings themselves, or they may be made to occur between the rings and the adjacent surfaces of the cylinders. The natural unevenness of the two cylinders at their lower ends will provide a suitable opening, as 20, at this point thru which air may enter the space beneath the receding parts during the removal of the shell.

An annular cover piece, 21 having a central aperture 22, is provided for covering the

space between the upper ends of the cylinders 7 and 13 and for receiving such blows as may be applied for driving the shell into the earth. This cover piece may be made detachable to facilitate the independent removal of the cylinders if desired, and an opening 23 may be provided either thru the cover piece 19 or thru the adjacent wall portion of one of the cylinders for the circulation of air into the space between the two cylinders.

It is to be noted further in connection with this invention that the shell herein shown and described may be readily and successfully employed in connection with the making and sinking of pre-cast piles:

Shells constructed in accordance with this invention may be appropriately supported above ground and employed as moulds for the formation of any number of pre-cast piles and the concrete material be placed within and allowed to set. Then the shells may be removed by simply drawing them off longitudinally from the hard concrete. If desired the concrete may be reinforced by bars or other devices 24 extending longitudinally therethru and placed within the mould before the introduction of the concrete material.

The taper of the interior of the shell will greatly facilitate the removal of the shell after the concrete has hardened.

The same shells which were used as moulds, or other similar shells, may then be used for driving the pre-cast piles into the earth, the shells being simply telescoped over the piles and one of the driving points 'G' being affixed at the lower end. The blows necessary for driving the pile may be delivered upon the upper annular edge of the shell so as to protect the concrete material during the driving operation, or a suitable driving head, 25, may be placed over the upper end of the shell to directly receive the hammer blows.

After the pile is driven the shell may be removed as has already been set forth.

It should be added that in pre-casting the piles the moulds employed, may, if desired, be of much lighter and cheaper construction than the shells which are employed for the driving operation, as suggested by the light shell 26 which is of uniform thickness illustrated in Fig. 13, the prime requirement being simply that the completed pre-cast piles, as seen in Fig. 14, be of such an exterior size and shape as to properly fit within the driving shells.

Where set, or hardened, concrete is being dealt with, as in the case of pre-cast piles, the driving shell may be forced downwardly over the hard surface of the pile until a desirable resistance is encountered by the taper of the shell. Then the driving head 25 may be placed in position over the upper end of

the shell and if not in actual contact with the upper end of the body of concrete suitable fillers, as 27 may be interposed so that the blows which are ultimately struck upon 5 the driving head are transmitted partly to the shell and partly to the body of concrete. The resistance offered by the interior tapered surface of the engagement of the shell with the whole exterior surface of the pile will 10 absorb a very considerable proportion of the power of the blows and thus will lessen the possibility of injury to the concrete such as might occur if the full force of the blows was applied directly to the upper end of the 15 concrete body.

In both cases the vibration of the shell under the repeated hammer blows used in the driving operation is sufficient to maintain the shell suitably loosened from the 20 concrete and thereby enable the easy removal of the shell.

Just before endeavoring to remove the shell from the body of concrete the driving head may be removed and suitable blows 25 dealt the concrete body for further loosening the concrete from the shell.

In using the shells as moulds for pre-cast piles, the lower ends of the shells may, if desired, be closed by a simple sheet metal cap member, 28, or by cone shaped cap members, 30 as 29, Fig. 16. By using the cone-shaped cap members the lower end of the completed pile will be pointed, as indicated at 30, in Fig. 17. Pointed piles of this kind may be 35 used with the tapered driving shells L and without the use of the metallic driving points G, as suggested by the illustration Fig. 18. In this instance the lower annular edge of the driving shell, as at 31, is preferably bevelled to correspond with the incline of the 40 point of the pile and to thus facilitate the entry of the pile and the shell into the earth.

If desired a light metal cover, as 32, may be provided for covering the point 30 of the 45 concrete and for providing a smoother surface for entry in to the earth.

In Fig. 12 is illustrated a pile shell which is of rectangular cross section, and it is understood that the walls of this shell are 50 tapered longitudinally from end to end substantially as has been already described. Fig. 12 also introduces certain irregularities, as indicated at 33 and 34 in said figure, the irregularity 33 consisting of a rib extending longitudinally of the pile at one side, while the irregularity 34 consists of a longitudinal groove-shaped portion at the opposite side of the shell. The interior walls of each of these parts, of course, tapers 55 the same as the main walls so that the whole of the interior of the shell tapers gradually and reduces in size toward the upper end of the shell.

Piles made by the use of shells such as 60 65 are indicated in Fig. 12 may be driven in

such close proximity to each other that the rib 24 formed by the part 33 of one pile will engage within the groove formed by the part 34 of the adjacent pile and thus produce a continuous wall.

Driving shells of this character may be employed either for the casting of piles within the earth or for the sinking of pre-cast piles.

Retaining walls, foundation walls, etc., or even ordinary building walls, may be produced in this manner, and the taper of the shells used in forming the independent piles will enable the removal of the shells with such efficiency as to leave the piles in proper condition for effectively co-operating with each other to provide a continuous bond between the piles such as has not been possible of attainment with the use of pile shells as heretofore employed.

Wherever in the claims hereto appended the pile shell is referred to, it is to be understood that this shell may be either of circular cross section or of rectangular cross section unless specifically described, as being of rectangular cross section, also that it may contain irregularities in its cross section such as are suggested for example by the parts 33 and 34 in Fig. 12 of the drawings.

Of course other forms of irregularities, or other cross sectional contours may be employed all within the scope of the claims.

As indicated at 35 in Fig. 10, the edge portions of the sheet 16 may be bevelled off so as to insure the formation of an air passage at the point 20 when the sheet is rolled into cylindrical form.

As many changes could be made in this construction without departing from the scope of the following claims, it is intended that all matter contained in the above description, or shown in the accompanying drawings, shall be interpreted as illustrative only and not in a limiting sense.

Having thus described my invention, what I claim as new and desire to secure by Letters Patent is:—

1. A pile shell which is of constant exterior diameter and which is of greater thickness at its upper end than at its lower end so that its interior diameter is less at its upper end than at its lower end.

2. A pile shell which is of substantially constant exterior diameter and which is of uniformly tapered interior diameter.

3. A pile shell consisting of an outer cylinder and an inner cylinder, the outer cylinder being of substantially constant dimensions thruout and the inner cylinder being tapered so that its inner diameter is less at the upper end of the shell than at the lower end of the shell.

4. A pile shell comprising a cylindrical member of constant dimensions thruout its length, and means fitted thereinto provid-
